ADDING MACHINE

Max Garbell, Chicago, Ill., assignor to Victor
Adding Machine Company, Chicago, Ill., a cor-
poration of Illinois

Application April 3, 1937, Serial No. 134,774

2 Claims. (Cl. 235—137)

This invention relates to adding machines, and is more particularly directed to a subtraction transfer for the accumulator mechanism.

As illustrated herein, the present invention involves mechanism which is engageable by the accumulator and which mechanism is under the control of a control key and operatively connected with the actuating mechanism of the machine to effect a carry when an accumulator pinion is rotated to carrying position.

The chief object of the invention is the provision of an improved means for effecting a transfer or carry during subtraction operations.

Another object is to provide a positive operating mechanism for a subtraction carry, and which mechanism serves to retain the accumulators while in their normal or carried positions.

A further object is the provision of operating mechanism for a subtraction carry, which, when moved, is restorable at the start of the subsequent operating stroke of the machine and during the time the accumulator is free of the carry mechanism and moving into engagement with its respective racks.

And a still further object is the provision of a subtraction carry mechanism which is conditioned by the accumulator mechanism under the control of the accumulator and actuated by the actuating mechanism of the machine.

Referring to the drawings:

Figure 1 is a top plan view of an adding machine showing a portion of the casing thereof broken away to illustrate my improved subtraction mechanism attached thereto.

Figure 2 is a longitudinal sectional view taken substantially on the line 2—2 of Figure 1.

Figure 3 is an enlarged detail side elevation of the subtraction carry mechanism, illustrating its position after a subtraction carry.

Figure 4 is a detail cross-sectional view taken substantially on the line 4—4 of Figure 2.

Figure 5 is a detail cross-sectional view taken substantially on the line 5—5 of Figure 2.

Figure 6 is an enlarged partial detail sectional view of the accumulator and carry mechanism shown in Figure 4.

Figure 7 is an enlarged partial detail perspective view of the accumulator and accumulator mechanism with the subtraction carry mechanism controlled thereby.

Figure 8 is a side elevation of the machine with the casing in section and illustrating the operative connections between the actuating mechanism of the machine and the subtraction carry

mechanism, and also the operative connections between the signal keys and accumulator.

Figure 9 is a view similar to Figure 8 illustrating a changed position.

Figure 10 is an enlarged plan sectional view of 5 the operative connections shown in Figure 8 taken on the line 10—10.

Figure 11 is an enlarged plan sectional view taken on the line 11—11 of Figure 13.

Figure 12 is a view of the left hand side of the 10 machine with the frame in section, illustrating the connections between the actuating mechanism and the subtraction carry mechanism operable with those connections shown in Figure 8.

Figure 13 is an enlarged detail side elevation of 15 the parts shown in Figure 3, illustrating the position they assume when the accumulator is clear.

Figure 14 is a view in side elevation similar to Figure 8, illustrating the position the parts assume when the subtotal key is depressed. 20

Figure 15 is a view similar to Figure 14 showing a changed position.

Figure 16 is a partial detail view of the parts shown in Figure 14, illustrating the position they assume when the subtraction key is depressed. 25

Figure 17 is a partial detail view of the parts shown in Figure 16, illustrating a changed position.

Figure 18 is an enlarged partial detail view of the subtraction carry mechanism and the parts 30 coacting with the accumulator.

Figure 19 is an enlarged detail perspective view of the lower portion of the four control keys and the signal rack.

Figure 20 is an enlarged detail perspective view 35 of the clearing control arm and the parts associated therewith extending to the repeat key.

Figure 21 is a view in side elevation of the parts shown in Figure 20.

Figure 22 is an enlarged detail sectional view of 40 the control disc showing the pins carried thereon and the arm controlled thereby.

Figure 23 is an enlarged detail perspective view of the arm controlled by the disc for effecting the restoring of the slides carried on the racks. 45

Figure 24 is an enlarged detail cross-sectional view taken on the line 24—24 of Figure 8.

My improved subtraction carry mechanism is shown applied to an adding machine of the key-set type and operable with an accumulator that 50 is moved into and out of engagement with reciprocating racks. So much of the machine is shown, as is necessary for a clear understanding of the cooperating parts for effecting the engagement and disengagement of the accumula- 55

tor operable by the actuating mechanism of the machine and for varying the time of engagement and disengagement of the accumulator under the control of the control keys, and also the operable connections cooperating with the actuating mechanism for setting the subtraction mechanism preparatory to a subtraction carry.

The construction of the control mechanism shown herein for effecting the engagement and disengagement of the accumulator with the racks is somewhat similar to that shown in my application, Ser. No. 121,132, filed January 18, 1937, but in this instance the control mechanism retains the accumulator normally out of engagement with the racks and is moved to bring the accumulator into engagement for movement with the racks at predetermined intervals depending upon the desired operation of the machine. Further there are means coacting with the control mechanism and operable after totaling operations for effecting the disengagement of the accumulator with the racks.

The parts which are similar to those disclosed in the application above referred to, are as follows: depressible digit keys 30, racks 31 controlled thereby, slides 32 carried on each of the racks and a type bar 33 controlled by each of the racks, the accumulator 34 and its cooperating mechanism for retaining or effecting the release of the racks, accumulator control mechanism and printing mechanism. The digit keys 30 are depressed to limit the movement of their respective racks 31 and the actuator shaft 35 is then oscillated by the forward and return movement of a motor or handle 36 secured to this shaft. This oscillation of the actuator shaft causes the oscillation of a disc 37 fixed to a shaft 38 carried in the side plates A and B of the machine. The disc 37 is operatively connected to the actuator shaft 35 by a link 39 and this disc 37 normally controls the operation of the accumulator control mechanism 40 to selectively effect engagement and disengagement of the accumulator 34.

The accumulator control mechanism comprises a pair of mesh-controlling cam plates 25 secured to each end of a shaft 88 supported in the side plates A and B of the machine. The cam plates 25 are each provided with a cam slot 25a through which the ends of the accumulator shaft extend and these cam slots are arranged to retain the accumulator in lowered position when the cam plates 25 are in their normal positions (Figs. 8, 14 and 16). A link 26 is pivoted to one of the cam plates 25 at 25b and is arranged for sliding movements on the side plate A by means of the slot and stud connection indicated at 26a. This link 26 has a substantially U-shaped member 27 pivoted thereto at 27a and is held in raised position thereon by a spring 28 attached to the pivot 25b and to a pin 86 carried by the U-shaped member 27 forwardly of the pivot 27a. The upper leg of the U-shaped member 27 is provided with an ear 82 which is normally out of the path of pins 44 and 46 carried by the disc 37 and the lower leg of the U-shaped member has a lug 29 which is normally in the path of these pins 44 and 46.

As the machine is operated for addition, the forward stroke of the handle 36 (Fig. 9) will carry link 39 therewith and disc 37 will be rotated counterclockwise approximately 180°, and at near the limit of its rotation, pin 46 will engage lug 29 and pull the U-shaped member 27 and link 26 rearwardly to swing the mesh-controlling cam plates 25 therewith and cause the accumula-

tor to be carried upward by the cam slots 25a to engage the slides 32. Upon the restoring stroke of the handle 36, disc 37 is returned and pin 46 will be carried away from the lug 29 and pin 44 which is approximately diametrically opposite 5 pin 46 on the disc 37 will be carried to engage the other side of lug 29 at near the return limit movement of disc 37 to restore the control mechanism 40 and cam plates 25 to disengage the accumulator from the slides 32. The lower 10 leg of the U-shaped member 27 is provided with a pin 29a at its free end portion and is adapted to be engaged by an arm C under the control of the total and subtotal keys 47 and 48, respectively, and by an arm 112 under the control of the subtraction key 50 for the purpose of selectively positioning ear 82 with respect to pins 44 or 46, as will be later described.

The accumulator 34 carries pinions 41 which are bodily moved into and out of mesh with the 20 respective slides 32, the accumulator frame 42 being pivotally mounted on a shaft 43, and movable about this shaft under the control of the mesh-controlling cam plates 25 to bring the pinions 41 into and out of mesh with the slides 25 (Figs. 2 and 3). When the frame 42 is lowered, the pinions 41 are out of mesh, and when it is raised, the pinions are in mesh (Fig. 18).

The up and down movement of the accumulator frame 42 is effected by means of the disc 37, 30 (Figs. 8, 9, 16 and 17), when one of the pins 44, 45 or 46 thereon engages to effect movement of the accumulator control mechanism 40 to cause the engagement and disengagement of the accumulator pinions 41 at the proper time. When the accumulator control mechanism is moved rearwardly (Fig. 9), the accumulator pinions 41 are brought in mesh with the slides 32 and when the accumulator control mechanism is in the forward position (Fig. 8), the accumulator 40 pinions 41 are out of mesh with the slides.

The machine illustrated is capable of performing adding, totaling, subtotaling, repeat and subtracting operations, and for each of these operations, the accumulator is arranged to be brought 45 into engagement with the slides 32, and to be carried out of engagement therewith at the proper time, in accordance with the operation that is being performed.

The accumulator control mechanism 40 is arranged to be conditioned by depressing control keys which selectively determine the time of engagement of the accumulator 34 with the slides. The usual adding operations are performed without depressing a control key; in the total operation the total key 47 is depressed; the subtotal operation is performed by depressing the subtotal key 48; in the repeat operation the repeat key 49 is depressed; and in subtraction operations the subtraction key 50 is depressed.

The depression of two of the control keys, namely, the total and subtotal keys, effects the movement of the control arm C, which in turn serves to clear the keyboard to restore any depressed digit keys prior to a total or subtotal 65 operation, and the free end of the control arm C engages pin 29a of the U-shaped member 27 to selectively position the ear 82 with respect to pins 44, 45 and 46 on disc 37.

The normal adding, totaling and subtotaling 70 operations are similar to those disclosed in my application referred to, but as illustrated herein, the accumulator is normally out of engagement with the slides and is brought into engagement therewith at the proper time, being controlled by 75

the accumulator control mechanism which is also selectively positioned by the control keys to effect the desired operation.

It is while the accumulator is in raised position (Figs. 7 and 18), and controlled by the movements of the racks and slides that each of the pinions 41 thereof may effect the movements of a tens transfer arm 51 and a zero lock arm 52. All of the pinions except the first pinion of lowest order of the accumulator have a pair of discs 53 and 54 secured for movement therewith. The disc 53 is provided with substantially diametrically opposed pins 55 and 56, with the pin 55 extending to the right or in the direction of lowest order, and the pin 56 extending to the left or in the direction of highest order, while the disc 54 is provided with a peripheral recess 57.

As the accumulator consists of a plurality of units each comprising a pinion 41 and a pair of discs 53 and 54, it is thought that a description of one and its cooperating parts will suffice for a description of all.

The pin 55 of the disc 53 is arranged to normally effect a tilting movement of the tens transfer arm 51 by direct contact therewith, while the pin 56 is arranged to also effect movement of the tens transfer arm 51 through an arm 58 connected to the tens transfer arm. The arm 51 is controlled by the pin 55 and the arm 58 is controlled by the pin 56, as will be later described. The tens transfer arm 51 is pivoted on a shaft 59 carried in the side plates A and B of the machine, while the arm 58 is pivoted on the accumulator shaft 43. The arms 51 and 58 are connected together by a slot and pin connection at 60, so that the movement of one or the other of the arms will control the movements of a detent 61 pivoted on a shaft 62 carried by the side plates A and B. The zero lock arm 52 is also pivoted to the accumulator shaft 43 and has a rearwardly extending portion 63 provided with an ear 64 that serves to coat with an ear 65 formed on each of the racks 31. The ear 64 on the extending portion 63 of the zero lock arm is adapted to engage the ear 65 of the rack when the peripheral recess 57 of the disc 54 of the accumulator registers with a pin 66 on the free end of the zero lock arm 52.

When the machine is clear (Figs. 2 and 18), the tens transfer arm 51 and the zero lock arm 52 are in their lowered positions so as to be in the path of and controlled by the accumulator when the accumulator is raised and its pinions 41 are in mesh with the slides.

During normal adding operations, the selected 55 digit keys are depressed, then the handle 36 is pulled forwardly and the slides 32 are carried rearwardly with the racks 31, which are arrested by the depressed digit keys 30, and at near the limit of the forward stroke of the handle, the 60 accumulator frame 42 is rocked upwardly to effect engagement of the pinions 41 of the accumulator 34 with the slides 32. During the return stroke of the handle, the slides and racks will be restored and run into the accumulator the 65 amounts set up in the machine and at near the end of the return stroke of the handle, the accumulator will drop out of mesh with the slides.

When the accumulator is raised to engage the slides, a cam 67 on the tens transfer arm 51 is then in the path of turning movements of the pin 55 carried on the disc 53 of the coacting accumulator unit. During the rotating movements of the accumulator under the control of a slide and rack, should the pin 55 be brought to engage 70 the cam 67, it will tilt the tens transfer arm 51

and effect the release of the detent 61 coacting therewith. During this time the rack has been carried away from the extension 61a of the detent 61 to permit the ear 68 of this detent to move out of the notch 69 to notch 70 of the tens transfer arm under the control of a spring 71 connected to the arm 51 and detent 61 (Fig. 3).

A slide lock arm 72 is arranged to be controlled by the tens transfer arm 51 and is pivoted adjacent thereto on the shaft 59 and has a lug 72a which is normally urged into engagement with the tens transfer arm 51 by a torsion spring 72b. When the tens transfer arm 51 is in its tilted position (Fig. 3), the slide lock arm 72 is carried therewith by reason of the torsion spring 72b and an ear 73 at the free end of the slide lock arm 72 is then carried out of the path of a lug 32a on the slide 32. This movement of the slide lock arm 72 effects a release of the slide 32 and an addition carry to the accumulator by permitting the slide to move beyond its normal position, as is more clearly pointed out in the application above referred to. The tens transfer arm 51 and slide lock arm 72 remain in their tilted positions with the slide 32 in advance thereof until near the end of the restoring stroke of the handle 36 when the ears 65 of the racks 31 engage the extensions 61a of the detents 61. This engagement of the detents restores them with their ears 68 out of the notch 70 and into the notch 69 and by reason of the spring 71, the tens transfer arm 51 is restored, which in turn carries the slide lock arm 72 to normal position. Then the slides which have been permitted to pass the ear 73 of the slide lock arm 72 are restored after the accumulator 34 has been carried downwardly out of mesh with the slides. This is accomplished by a pin 74 fixed to the control disc shaft 38 engaging a shoulder 75 of an arm 76 pivoted on the shaft 38 and which arm is connected at 77 to a rocker arm 78 pivoted at 79 to the side plate A, and has its other end connected to a slide restoring bar 80 pivoted at 81 between the side plates A and B and extending across the entire series of slides.

Subtraction and subtraction carry mechanism

When a subtraction operation is to take place, the subtraction key 50 is depressed which effects the movement and positioning of the U-shaped member 27 of the accumulator control mechanism 40, so as to carry an ear 82 thereof into the path of movement of the pin 44 carried on the disc 37 and also position a pin 86 into the path of an arm 84 (Fig. 16).

When operating the machine and at the start of the forward stroke of the handle 36, the ear 82 is engaged by the pin 44 to carry the accumulator control mechanism 40 rearwardly and rock the accumulator frame 42 upwardly with the accumulator pinions 41 in mesh with their respective slides. As these slides 32 are carried rearwardly during the forward stroke of the handle, the depressed digit keys 30 determining the amount set up in the keyboard to be subtracted, will limit the rearward movement of the racks and slides. This rearward movement of the slides will run out of the accumulator, the amount to be subtracted, and during this movement of the accumulator, should a pin 55 of an accumulator unit be rotated to engage the cam 67 and tilt the coacting tens transfer arm 51, the notch 69 thereof will be free of the ear 68 of the detent 61 and this detent will be urged by its spring 71 with its ear 68 into the notch 70.

of the tens transfer arm 51 and retain the same in tilted position (Fig. 3). At near the end of the forward stroke of the handle, a pin 83 forming the pivot for the link 39 on the disc 37 will engage to swing the depending arm 84 carried on a stud 85 extending from the side plate A of the machine. The free end of this arm 84 will engage pin 86 of the accumulator control mechanism 40 and exert a pressure thereagainst to restore the same to lower the accumulator frame and carry the pinions 41 of the accumulator out of engagement with the slides 32. As the accumulator is lowered to normal position out of engagement with the slides 32, it is brought into meshing engagement with a plurality of segments 87 that normally serve to retain the units of the accumulator in the position to which they have been moved, and which segments also serve as a subtraction carry, as will be presently described.

Each of the segments 87 is arranged for pivotal movements on a shaft 88 supported below the accumulator in the side plates A and B of the machine, and these segments are aligned for meshing engagement with the pinions 41 of the accumulator 34. The segments 87 each have their lower end portions pivoted at 89 to a connecting link 90 which has its other end pivoted at 91 to a depending arm 92 that is pivoted for swinging movements on a shaft 93 supported adjacent the accumulator in the side plates A and B of the machine. Each of the links 90 carries an arm 94 pivoted thereto at 95, and a spring 96 which has its ends secured to the link 90 and arm 94 serves to support the arm in raised position on the link. The link 90 is guided through a comb 97, while the arm 94 is guided through a comb 98. This comb 98 is provided with a plurality of slot openings 99 (Fig. 7), which serve to retain the arms 94 aligned with ears 100 formed on a leg 101 of each of the detents 61.

During each operation of the machine, the shaft 93 is rocked to exert a tension to the depending arms 92 through the springs 102, but during the time that the detents 61 remain in their normal positions (Figs. 2, 13 and 18), normal subtraction operations take place in the accumulator.

50 Operation of subtraction carry mechanism

When a subtraction carry is to occur during subtraction operations, the pin 55 of one of the units of the accumulator will have moved to engage the cam 67 to tilt the tens transfer arm 51 and carry the notch 69 thereof out of the path of the ear 68 of the detent 61 which permits the detent to be urged upwardly by its spring 76 in the same manner as when adding. While the arm 94 and link 90 are released from the detent 61 coacting therewith, they remain in their normal at-rest positions until at near the limit of the forward stroke of the handle, and at which time, the arm 84 is engaged by the pin 83 of the control disc 37 to restore the accumulator control mechanism 40 and cause the accumulator frame to be lowered with the pinions 41 of the accumulator in mesh with the segments 87. The swinging movement of the arm 84 when engaged by the pin 83, causes the free end of this arm 84 to engage the pin 86 which restores the accumulator control mechanism 40 after a subtraction operation (Fig. 17). After the accumulator has been lowered, the actuating mechanism carried by the actuator shaft 35 is then brought into play which effects the move-

ment of the released link 90 and arm 94 to effect a counter-clockwise movement of the coacting segment 87 for a carry. All of the remaining segments 87 will be retained through their link and arm connections abutting the ear 100 of their respective detents 61. When the detent 61 is in its raised position (Fig. 3), the ear 100 of the leg 101 thereof is carried out of the path of the arm 94, and this arm and its coacting link 90 are then free to be moved rearwardly. In order to urge the link 90 and arm 94 rearwardly for a carry, each of the depending arms 92 are yieldingly connected by a spring 102 to a member 103 fixed to the shaft 93, and the shaft 93 is provided with depending arms 104 fixed at each end thereof outwardly of the side plates A and B. These depending arms 104 each have a link 105 pivoted thereto at 106, and the other ends of the links 105 are each pivoted at 107 to a bell-crank 108 that is supported for pivotal movements on a stud 109 fixed to each of the side plates A and B of the machine. The actuator shaft 35 carries members 110 and 111 fixed to each end of the shaft adjacent the side plates A and B, and these members 110 and 111 are brought into engagement with the bell-cranks 108 at near the end of the forward stroke of the handle 36. These members 110 and 111 will rock the bell-cranks 108 rearwardly to exert a pull on the links 105 and the depending arms 104 to rock the shaft 93 and exert a pull on the spring 102 which, in turn, force the arms 92 and links 90 to rock the segments 87 counter-clockwise for a carry (Fig. 3). While the arm 94 carried on the link 90 is in abutting engagement with the ear 100 of the detent 61, it will prevent the segment 87 from rocking on its shaft 88. When the ear 100 of the detent 61 has been moved out of engagement with the arm 94, this arm and link 90 are then free to move rearwardly and the tension of the spring 102 exerted by the rocking movement of the shaft 93 will then cause the segment 87 to rock on its shaft 88 and effect a carry to the coacting accumulator pinion 41.

An arm 112 is carried on the side plate A on a pivot 113 and this arm is rockable by the depression of the subtraction key 50 for conditioning the accumulator control mechanism with the ear 82 of the U-shaped member 27 thereof between the pins 44 and 45 so that pin 44 will immediately engage ear 82 and carry the control mechanism rearwardly to raise the accumulator in mesh with the slides 32 at the start of the forward stroke of the handle 36.

A tension spring 114 is arranged to coact with each of the bell-cranks 108, and this spring has one end secured to the pivot 107 and its other end secured to the base of the machine below the pivot 109. These springs 114 serve to hold the bell-cranks 108 in the position to which they have been moved to retain the shaft 93 in its normal position or to retain a tension on the depending arms 92.

When the members 110 and 111 of the actuating mechanism have engaged the bell-cranks 108, they will have rocked them rearwardly, so that when these members are restored to their normal positions, the bell-cranks will remain in the positions to which they have been rocked. This rocked position of the bell-cranks retains the link 90 and arm 94 in advanced position while the tens transfer arm 51 and detent 61 are restored to their normal positions, as above described.

Assume now that a subtraction carry has occurred, the free end of the arm 94 is then under the ear 100 of its coacting detent 61 and remains in this position. During the time that 5 the racks 31 and slides 32 are being restored to their normal positions, the ears 65 of the racks engage the extensions 61a of the detents 61 to move them downwardly from Figure 3 position to Figure 13 position. The restoring movement 10 of the detent 61 restores the tens transfer arm 51 to normal position, and the detent depresses arm 94 which is permitted to yield by reason of the spring 96, and the link 90 and arm 94 remain in this advanced position until the next 15 operation of the machine.

During the succeeding operation, the bell-cranks 108 are restored to their normal positions after the accumulator has been raised into mesh with the racks. This movement of the 20 accumulator, which is accomplished by engagement of one of the pins on the control disc 37 with the ear 82 of the U-shaped member 27 forming part of the control mechanism, carries a pin 115 fixed to mesh-controlling cam plate 25 into engagement with a depending pawl 116 pivotally carried on the link 105 at 117 (Figs. 8 and 9), and which pawl is normally urged toward the pin 115 by a spring 118 fixed to the pawl 116 and link 105. As the accumulator control 30 mechanism 40 is moved to cause engagement of the accumulator with the slides prior to the restoring of bell-cranks 108, the pin 115 on cam plate 25 will be brought into engagement with the pawl 116 and effect a forward movement of the links 105 to rock the shaft 93 and depending arms 92 to restore the advanced link 90 and arm 94 to normal position. When thus restored, the arm 94 will then be urged upwardly by its spring 96 with the free end of the arm 94 in 40 abutting engagement with the ear 100 of the detent 61.

When a carry occurs during subtraction operations, the pinions 41 of the accumulator will have been rotated while engaged with the slides 45 32 until a pin 55 of an accumulator unit has engaged the tens transfer arm 51 to tilt this arm and position the coacting detent 61 out of engagement with the arm 94 of the subtraction carry mechanism. As the accumulator 34 is 50 lowered out of mesh with the slides 32, it is brought into mesh with the segments 87 and it is at the end of the forward stroke of the actuator shaft 35 that the members 110 and 111 engage the bell-cranks 108 to effect the carry, as above 55 described.

Should the units of the accumulator 34 be so positioned that when a subtraction carry of one of the units occurs, it positions the adjacent unit of higher order for a carry; the pin 56 of this 60 adjacent accumulator unit will be carried into engagement with its coacting arm 58 and effect a downward rocking movement of this arm 58 to tilt the tens transfer arm 51 by reason of its slot and pin connection 60 and will effect the 65 release of the detent 61 coacting with the tens transfer arm 51, and, when released, the ear 100 of this detent will be carried out of the path of the coacting arm 94. As all of the depending

arms 92 remain under the tension of their springs 102 by reason of the shaft 93 remaining in its rocked position, a rocking movement of the coacting segment 87 will occur for a carry to the unit of higher order adjacent the one that has been set up for a carry under the control of a slide 32. 5

In my improved subtraction carry mechanism, it is always possible for this mechanism to effect a "zip" throughout the units of the accumulator 10 or for a carry from one unit to an adjacent unit of higher order throughout the series, as the shaft 93 is always positioned to maintain a tension against the links 90 and segments 87 at the completion of each subtraction operation of 15 the machine.

While I have shown control keys operable for effecting the positioning of the accumulator control mechanism 40 for movement with the driving mechanism of the machine, the same has not 20 been fully described herein, as it has been fully disclosed in my application above referred to.

I claim:

1. In an adding machine, an accumulator adapted to be reversely actuated for addition or 25 subtraction, comprising an accumulator wheel, a pivoted tens transfer arm adapted to be rocked by movement of the accumulator wheel in transferring operations, a pivoted detent holding the transfer arm in normal position and movable to 30 hold the transfer arm in moved position, a spring connecting the detent with said transfer arm providing means for moving the detent by movement of said transfer arm, a subtraction carry mechanism comprising a shiftable pair of arms pivoted together in end to end relation and with one of said arms normally abutting said detent, a carry segment normally engaged by the accumulator wheel and operatively connected to be moved by movement of the said pair of pivoted together 40 arms, and tensioning means urging to shift the said pivoted together arms upon each operating stroke of the machine, said tensioning means effecting the shifting of the said pair of pivoted together arms and movement of the segment to 45 effect a carry when said detent is moved to release the said pair of arms by movement of said tens transfer arm. 55

2. In an adding machine, an accumulator adapted to be reversely actuated for addition or 50 subtraction comprising an accumulator wheel, a movably mounted tens transfer arm adapted to be moved by movement of the accumulator wheel in transferring operations, a detent holding the transfer arm in normal position and movable to 55 hold the transfer arm in moved position, a pair of shiftable members pivoted together in end to end relation with one of said members normally in abutting relation with said detent, a carry segment movable by movement of said shiftable 60 members and engageable by the accumulator wheel, tensioning means for shifting said members, said transfer arm when moved effecting movement of the detent and releasing the shiftable members to the action of said tensioning 65 means to effect a carry. 70

MAX GARRELL.
